METHOD OF AND APPARATUS FOR FLASHING BRICK

Original Filed May 17, 1920

By his Attorney Conrad Dreher
John E. Hubbell

UNITED STATES PATENT OFFICE.

CONRAD DRESSLER, OF CLEVELAND, OHIO, ASSIGNOR TO AMERICAN DRESSLER TUNNEL KILNS, INC., OF NEW YORK, N. Y., A CORPORATION OF NEW YORK.

METHOD OF AND APPARATUS FOR FLASHING BRICK.

Application filed May 17, 1920, Serial No. 381,003. Renewed July 17, 1923.

To all whom it may concern:

Be it known that I, CONRAD DRESSLER, a subject of the King of Great Britain, and resident of Cleveland, in the county of 5 Cuyahoga and State of Ohio, have invented certain new and useful Improvements in Methods of and Apparatus for Flashing Brick, of which the following is a specification.

10 The object of the present invention is to provide for the flashing of brick in a continuous muffle heated kiln, and particularly in a continuous kiln of the Dressler type in which internal combustion chambers are located in the kiln chamber, and the heat transfer to goods passing through the kiln is wholly or mainly by a convection current circulation of the kiln atmosphere which serves as a vehicle for transmitting heat 20 from the combustion chambers to the goods.

The flashing of brick is a surface treatment which results in the formation of dark colored patches or streaks on the surface of the brick. This discoloration is caused by 25 the impingement of a reducing flame against the brick when the latter are at or in the neighborhood of the maximum temperature required for firing them.

In carrying out the present invention I 30 preferably employ a continuous tunnel kiln which differs from an ordinary Dressler kiln only as required for the maintenance of a reducing gas atmosphere in a high temperature flashing zone portion of the kiln 35 and in the cooling zone portion of the kiln adjacent the flashing zone, or at least in the portion of the cooling zone in which the brick are still hot enough to eliminate the flashing effect on exposure to an oxidizing 40 atmosphere.

The various features of novelty which characterize my invention are pointed out with particularity in the claims annexed to and forming a part of this specification. 45 For a better understanding of the invention, however, and the advantages possessed by it reference should be had to the accompanying drawings and descriptive matter in which I have illustrated and described a preferred form of apparatus for use in carrying out my invention.

Of the drawings;

Fig. 1 is a diagrammatic plan;

Fig. 2 is a section on the line 2—2 of Fig. 55 1; and

Fig. 3 is a partial section on the line 3—3 of Fig. 1.

The kiln A shown in the drawings comprises an elongated kiln chamber having an entrance door A¹ at one end, and provided at its opposite end with an exit chamber A², and with doors A³ and A⁴ at each end of the latter. The brick or other material to be treated in the kiln is carried through the latter on suitable cars B running on track 60 rails C. At each side of the pathway for the goods is located a combustion chamber D which preferably, and as shown, is of the type disclosed in my prior Patent No. 1170428. Each combustion chamber is provided, adjacent its end, remote from the entrance end of the kiln, with one or more gas inlets E. As shown, there are three gas inlets E from the gas supply piping E' to each chamber D. Each combustion chamber 70 D is also provided in the construction shown, with an air inlet F adjacent each gas inlet E. The ends of the combustion chambers adjacent the entrance end of the kiln are connected at their ends remote from the 80 combustion chambers proper, to headers G¹ having outlets G² opening to a conduit G³ running to a suitable draft creating device, such as a stack H for withdrawing products of combustion with a regulated draft 85 suction.

In the cooling zone portion of the kiln adjacent its exit end, heat absorbing pipes I are located at each side of the goods pathway. These open to the atmosphere at the 90 exit end of the kiln and are connected at their opposite ends to headers I' having outlets I² opening to a conduit I³ connected to the inlet of a fan or blower J. The latter is provided with a valved outlet J', and a 95 second valved outlet J². The outlet J' supplies air to the combustion chambers D, while the air issuing through the outlet J² is available for use in a brick drier or wherever else there may be a demand for 100 hot air. In so far as above described the kiln disclosed does not differ from a common form of the well known Dressler kiln except that in the ordinary Dressler kiln of the general kind shown the heat absorbing 105 pipes I extend into close proximity with the adjacent ends of the combustion chambers D, whereas in the construction illustrated the cooling pipes I are separated from the combustion chambers D by the length of the 110

flashing zone A—A. Combustible gas or oil is passed into the kiln chamber in the flashing zone portion of the latter. As shown this gas is supplied by the gas supply pipes 5 E' and branches E² thereof, which open to the kiln chamber at intervals along the length of the flashing zone.

As shown each branch pipe E² as well as each combustion chamber supply branch E¹⁰ is provided with an individual regulating valve E'. Gas outlets open from the kiln chamber adjacent the exit end of the latter. These may each comprise a short stack K and each is advantageously provided with a 15 regulating damper K'. Provisions are made, as by forming a port A¹⁰ in the entrance door A', for permitting a constant though restricted influx of air into the kiln chamber at its entrance end. While air may be passed 20 from the fan outlet J' to the combustion chamber inlets F in any suitable manner I prefer the special construction illustrated. This comprises conduits L located above the benches A⁵ at the sides of the goods pathway on which the combustion chambers D and cooling pipes I are placed. The body portion of each conduit L consists of clay pipe sections L' and coupling sleeves L² embedded in mortar in a brick walled box L³ 25 which rests on piers A' carried by the corresponding bench A⁵. Each conduit is connected at its combustion chamber end to a passage F' formed in the corresponding bench A⁵ running to the combustion chamber air inlets F. At its opposite end each, conduit L is connected through an expansion box M to a passage A⁶ in the bench which is in communication with the fan outlet J'. The expansion box M sets in a tray 30 N resting on the bench and formed with an aperture registering with the passage A⁶; sand in the trays N forms sand seals preventing air leakage into the kiln while permitting the expansion boxes M and the adjacent ends of the conduits L to move relatively to the benches A⁵ on changes in temperature of the apparatus. The conduits L absorb heat and thereby give additional heat 40 to the air passing through them. To increase this heat absorption and to improve the circulation in the flashing zone screen walls O are arranged between the conduits L and the goods pathway. The walls O are formed with ports O' which register with the spaces between the piers A'. The special 45 conduit construction described possesses the advantages that the air passing through it from the fan outlet J' to the combustion chambers is heated in its passage and with a minimum risk of air leakage into the kiln chamber. If the pipe L' cracks as it may 50 sooner or later under the thermal conditions to which it is subjected this cracking can result in but a comparatively small amount of leakage through the mortar in which the

pipe is imbedded and the wall of the brick casing enclosing the mortar and pipe. The gas supply pipes E' extend into the channels between the piers A'.

In the contemplated mode of operation of 70 the apparatus shown, the kiln chamber is normally filled by a train of brick carrying cars B inserted one at a time at regular intervals at the entrance end of the kiln and removed from the exit end of the kiln at corresponding intervals. In their passage 75 through the heating up zone of the kiln in which the combustion chambers are located, the brick are gradually heated up to the firing temperature. In this portion of the kiln 80 the brick are exposed to an oxidizing atmosphere. On passing into the flashing zone the brick are exposed to the atmosphere formed therein by the gas admitted to the pipes E² and the products resulting from 85 the union in combustion of a portion of this gas with the air passing into the flashing zone from the heating up zone. The amount of air thus passing into the flashing zone is normally restricted to an amount insufficient 90 for the complete combustion in the flashing zone of the gas supplied by the pipes E' so that a strongly reducing atmosphere is maintained in the flashing zone, and in the adjacent portion of the cooling zone. Ordinarily the amount of gas supplied to the 95 flashing zone should be such that with the air coming to the flashing zone from the heating up zone and the leakage of air into the exit end of the kiln, but little unburned gas will be drawn out of the kiln through 100 the outlets K.

In flashing brick the effect of the reducing flame is mainly to convert iron in oxide form in the clay to metallic iron or ferrous ferric oxide. While the novel method and apparatus described and claimed herein is especially useful in the flashing of brick, it is not restricted to such use but may be employed wherever a reducing atmosphere is 105 desired in the exit end portion of the chamber of a muffle heated kiln, as for example in forming metallic lustre glazes on ceramic ware.

While in accordance with the provisions 110 of the statutes I have illustrated and described the best form of my invention now known to me it will be apparent to those skilled in the art that changes may be made in the form of the invention disclosed without departing from the spirit of the invention, as the latter is set forth in the appended claims, and that certain features of the invention may sometimes be used to advantage without a corresponding use of 115 other features.

Having now described my invention, what I claim as new and desire to secure by Letters Patent, is:

1. The method of flashing brick in a con- 120

tinuous muffle heated kiln which consists in passing fuel and air for its partial combustion into a high temperature portion of the kiln chamber to thereby maintain a reducing gas atmosphere in said kiln chamber portion and in the portion of the cooling zone of the kiln in which the brick are at a temperature high enough to result in surface oxidation if exposed to an oxidizing atmosphere.

2. A tunnel kiln for burning and flashing brick and like purposes comprising in combination, a kiln chamber having a heating up zone, a flashing zone and a cooling zone, internal combustion chambers for heating the heating up zone of the kiln chamber, heat absorbing conduits for cooling the cooling zone of the kiln; means for maintaining an oxidizing atmosphere in the heating up zone of the kiln, and means for maintaining a reducing atmosphere in the flashing and cooling zones of the kiln.

3. Apparatus for flashing brick and like purposes comprising an elongated kiln chamber through which the material treated may be passed from one end of the chamber to the other, muffle heating means extending along a portion of the kiln chamber adjacent its goods entrance end, conduit cooling means for the portion of the kiln chamber adjacent its exit end, means for supplying fuel in gaseous form to the kiln chamber adjacent the high temperature portion thereof, means for providing a supply of air to the kiln chamber restricted to accomplish the incomplete combustion in the flashing zone of said fuel and means for withdrawing from the kiln chamber the unburned gases and products resulting from the partial combustion of the fuel supplied to the kiln chamber.

4. Apparatus for flashing brick and like purposes comprising an elongated kiln chamber formed with benches at its opposite

sides and a pathway for goods carrying cars between said benches, combustion chambers located on said benches near the entrance and central portion of the kiln, cooling pipes located above said benches in the portion of the kiln chamber adjacent its exit end, transverse piers formed on said benches between the combustion chambers and the cooling pipes conduits resting on said piers and connecting the cooling pipes to the combustion chamber whereby air preheated in the cooling pipes and in said conduits is delivered to the combustion chambers, fuel inlets to the combustion chamber, and means for supplying fuel in gaseous form to the interior of the kiln chamber comprising inlet pipes located in the spaces between said piers.

5. Apparatus for flashing brick and like purposes comprising an elongated kiln chamber formed with benches at its opposite sides and a pathway for goods carrying cars between said benches, combustion chambers located on said benches near the entrance and central portion of the kiln, cooling pipes located above said benches in the portion of the kiln chamber adjacent its exit end, transverse piers formed on said benches between the combustion chamber and the cooling pipes, conduits resting on said piers and connecting the cooling pipes to the combustion chamber whereby air preheated in the cooling pipes and in said conduits is delivered to the combustion chambers, fuel inlets to the combustion chamber, means for supplying fuel in gaseous form to the interior of the kiln chamber comprising inlet pipes located in the spaces between said piers, and means for withdrawing gases from the kiln chamber adjacent the exit end of the latter.

Signed at Cleveland, in the county of Cuyahoga and State of Ohio this 12th day of May A. D. 1920.

CONRAD DRESSLER.
